WITNESS:

R. M. Morris.

INVENTOR,

Ernest M. Whitcoo,

BY

Harry W. Brown.

ATTORNEY.

UNITED STATES PATENT OFFICE.

ERNEST M. WHITCOON, OF SPRINGFIELD, MASSACHUSETTS.

UMBRELLA.

1,289,334.

Specification of Letters Patent. Patented Dec. 31, 1918.

Application filed July 3, 1918. Serial No. 243,128.

To all whom it may concern:

Be it known that I, ERNEST M. WHITCOON, a citizen of the United States of America, residing at Springfield, in the county of Hampden and Commonwealth of Massachusetts, have invented certain new and useful Improvements in Umbrellas, a specification of which follows.

This invention relates to improvements in the construction of umbrellas. The object of the invention is to provide a device for quickly repairing the umbrella should a break occur at any one of the joints, either at the top part of the staff or handle, or at the point of pivotal connection of a brace with a rib, or at the point of pivotal connection between a brace and the runner.

The invention comprises a clip device which is designed to be quickly secured to the pivotal end of a brace or rib for attaching the rib or brace to the fixed collar at the upper end of the staff or to the runner, or for attaching a brace to the rib, should the brace or rib become broken at its pivotal connecting point. It is a well known fact that the joint or pivotal connecting ends of a rib or brace in umbrellas frequently become broken and that in order to repair the same it is necessary to practically dismantle the entire article. In the present invention it is not necessary to even remove the wire from the fixed collar or runner which forms the pivotal connection between the upper ends of the ribs and the inner ends of the runner. Should the end of a rib or brace in which the eye is located become broken it is only necessary to attach the clip at the point of fracture and connect the same to the collar, or runner, as will be described, depending of course where the break occurs.

Referring to the drawings:

Figure 1 is a detail side view of the repairing clip, a portion being in section on the line 1—1 of Fig. 2.

Fig. 2 is a view showing a portion of the frame work of an umbrella and the manner of using the repairing clip attached to the fixed collar, the runner and to the brace where it is connected to the rib.

Fig. 3 is an enlarged detail plan view of the fixed collar, or runner, illustrating the annular flange with the recesses therein and showing a clip on the end of a rib, or brace, about to be attached to the collar or runner.

Fig. 4 is a detail sectional view on the

line 4—4 of Fig. 3, showing the manner of attaching the clip to a rib or brace.

Fig. 5 illustrates the operation of attaching the repairing clip on a rib to the fixed collar.

Fig. 6 shows the clip after it has been attached with the ring for holding the clip in place.

Referring to the drawings in detail:

1 designates the staff or handle rod of the umbrella, 2 the slotted collar fixed thereto near its upper end, 3 the slotted runner, 4 one of the ribs, and 5 one of the braces; 6 is a view of the clip, as a whole, that is to be used for attaching a broken rib or brace to the collar or runner, or to each other. This clip is preferably formed from a blank of thin sheet metal as mild steel. This blank is designed for the purpose of crimping or bending around an end of a brace or rib should the eye portion become broken, as shown in Figs. 2, 3, 4, 5, and 6; the bent or crimped end which is folded around a brace is shown at 6', one side being carried over into the inside of the channel portion of the rib, or brace as shown in Fig. 4 at 7 for the purpose of forming a cylindrical shaped barrel portion 8 to prevent the clip from slipping on the brace or rib. This cylindrical shaped portion substantially fills the usual channel portion of a brace or rib. The outer end of the clip is split to form the fingers 9 and 10, and their outer ends are separated and curved inward toward each other to form the attaching hooks 11 and 12. 90

13 and 14 designate the ring of wire which is secured in the annular channel, or groove 15, of the runner or fixed collar. Should the end of the brace or rib become broken in which the eye is located, the clip 6 is attached thereto, as shown at 6'; the fingers 9 and 10 are opened as shown in Fig. 5, the hooks 11 and 12 are passed over the ring 13, the ring 16 is then slipped over the enlarged portion 17 from its position as shown in Fig. 5 to that shown in Fig. 6, whereby the hooks 11 and 12 will grip the ring 13 and securely retain the brace or rib attached to the fixed collar, or runner, as shown in Fig. 6. The same operation is carried out in 105 attaching a brace to a rib should that end of a brace become broken.

From this description it will be seen that I have produced a simple and inexpensive device for quickly repairing a broken rib or 110

brace of an umbrella without dismantling the same. An important feature of the improvement is the fact that the wire 13 does not have to be removed or replaced in order to make the repair.

It is to be understood that I do not limit myself to the use of the clip described herein for repairing an umbrella as the clip may, of course, be employed when the article is first assembled. A rib and brace are usually supplied with the clip or attachment thereon ready for inserting in making the repair.

What I claim is:

1. A device for the purpose described, comprising a blank of flexible material, one end being designed for bending around the usual grooved brace or rib of an umbrella and in a lateral direction to inclose the same; its other end being slotted to form curved fingers with ends which extend toward each other for attachment to the pivotal ring of the runner or collar, and means comprising a ring slidable on the fingers for closing the fingers to form a ring-like member for gripping the ring and for retaining the device in place on the collar or runner.
2. A device for the purpose described

comprising a flat blank of flexible material, one end being designed for bending around a brace or rib; its other end being slotted to form fingers with hook-shaped ends for attachment to the pivotal ring of the runner or collar, means comprising a ring slidable on the fingers for retaining the device in place on the collar or runner, the fingers having an enlarged portion over which the ring passes for attaching or releasing the fingers to the ring of a runner or collar, as described.

3. A clip device for the purpose described comprising a flat blank of flexible metal, one end of which is slotted to form fingers, said fingers being twisted out of the plane of the blank with relation to the other end of the blank, the fingers having an enlarged curved portion and a contracted or narrow portion to receive a runner ring for retaining the fingers in clamping or closed relation about the usual ring of an umbrella runner, and the other or non-slotted end of the blank being designed for bending around the broken end of an umbrella brace or rib for the purpose described.

ERNEST M. WHITCOMB.
